ABSTRACT OF THE DISCLOSURE

A multi-linked flexible connector of a heavy gauge material. The connector has elongated, flexible arms. The connector is completely insulated and when installed may be submersible and since the heavy gauge arms are flexible, they can be entered into even confined or inaccessible locations by bending to a convenient position in which the connecting cable is fixed. The installer may maneuver the compression end of the connector into any desirable position suitable for a crimping operation in a limited space.

BACKGROUND OF THE INVENTION

In prior constructions of relatively heavy gauge multi-arm connectors, it has been a problem of maneuvering the compression end of these heavy gauge connectors into various positions for crimping operations, especially in a limited space. Since each lead of the heavy gauge connectors was fixed to the other lead in common, it was difficult to maneuver the bulky connector unit to connect a number of cables. It was, therefore, awkward and sometimes impossible to make connections to the various connectors of the multi-connector element.

SUMMARY OF THE INVENTION

It is a principal object of the present invention to construct a relatively heavy gauge multi-arm connector, known as a flexible crab, which may be used and maneuvered into desirable positions for suitable crimping or other installation operations in limited spaces. The heavy gauge multi-arm connector is provided with a plurality of flexible arms each having connecting elements or conductors tied together by means of a tie rod or a bridge. The entire unit is covered with an insulating substance. The design may take the form of a tie bar having, for example, three or four elements affixed in a linear relationship or said elements arranged in a cluster formation.

The connecting end elements for the flexible arms can be several conductors, cable or wire. In addition, the connecting end elements may be of the compression type wherein the element is made of a ductile material and is suitable to accept various types of crimps. Furthermore, a mechanical clamp type may be employed where the element is secured to the connector by means of a screw and pressure plate. In addition, other end connecting elements may also be employed, such as a cone-type collet mechanical device which can secure the cable or element to the connector, or an end connecting element and adjacent cable, and each of which has a flat pad with aligned holes to enable the same to be bolted together. The flexible legs of the heavy gauge multi-arm connector are omni-directional and are of sufficient size to handle the maximum cable or wire to be connected to each of the connecting end elements.

It is therefore a principal object of the present invention to provide a multi-armed, heavy gauge connector, with said multiplicity of flexible arms having connecting end elements.

It is another object of the present invention to provide a connector which is completely insulated and when in-

2

stalled can be submersible in water or located underground.

It is a further object of the present invention to provide a variety of possible cable sizes to be inserted in the connecting end elements or conductor connecting receptacles of the flexible arms by the use of soft aluminum inserts or shims which will compensate for the difference between the internal diameter of compression end of the connecting end elements and the diameter of any smaller cable.

BRIEF DESCRIPTION OF THE DRAWINGS

FIG. 1 is a partial elevation, partial sectional view of a multi-linked flexible connector of heavy gauge material constructed in accordance with the teachings of this invention.

FIG. 2 is a sectional view taken along the lines 2—2 of FIG. 1.

FIG. 3 is a fragmentary view of a detail of construction of FIG. 1.

FIG. 4 is an alternate embodiment of the present multi-linked, flexible connector of heavy gauge material.

FIG. 5 is a fragmentary view of a detail of construction shown in FIG. 4.

FIG. 6 illustrates a partial sectional and a partial elevational view of a connecting end element having a cable secured therein.

FIG. 7 is an alternate construction, being a partial sectional and a partial elevational view of a connecting end element showing another method of affixing a cable therein.

FIG. 8 is a sectional view of another type of end connecting element in which a cable is secured thereto and

FIG. 9 is a partial elevation and sectional view of another type of end connection for the present flexible conductor.

DESCRIPTION OF THE PREFERRED EMBODIMENT

The connector 10 is preferably constituted of aluminum but may also be fabricated of copper and comprises a tie bar 12 having a plurality of flexible legs 14 depending therefrom. Each of the legs 14 is preferably circular in cross-section so that the bending of each of the legs may be omni-directional. At the free end of each of the flexible legs 14 is an enlarged connecting end element 16 which is provided with a reentrant opening or passageway 18 extending from the outer end of the connecting element 16 inwardly. The connecting elements 16 that are not in use may be sealed by means of a cap 20. As seen in FIGS. 3 and 5, each of the flexible legs 14 is secured to the tie bar 12 by means of welding or brazing at location 22. In addition, FIGS. 3 and 5 also illustrate the flexible legs 14 as being, respectively, solid or stranded, and also applicable to both FIGS. 1 and 2. It should be noted that insulating cover 24 surrounds the tie bar 12 as well as flexible legs 14.

FIG. 4 shows an alternate construction constituting a cluster of three flexible legs 14 secured together by means of the tie bar 12.

FIG. 6 shows a connecting end element 16 in detail being of the compression type wherein the element is made of a ductile material and is suitable to accept various types of crimps 27 in order to affix the cable or wire 28 within the passageway 18 in the connecting end element 16. FIG. 7 is an alternate embodiment of the connecting end element 16 which discloses a structure comprising a mechanical clamp wherein a pressure plate 30 moved by a screw 32 is adapted to engage a surface of the cable or wire 28. The screw 32 is screw-connected in a threaded opening 34 in the insulating cover 24. Thus, the rotation of the screw 32 in a selected direction will

either clamp the cable or wire 28 in the passageway 18 or unclamp the same therein.

FIG. 8 illustrates a collet-type end connection for the present multi-linked flexible connector as an alternate for element 16 in which two sleeves 36 and 38 and two compression nuts 40 and 42 and the nipple 44 have a coaxial bore 46 accept the cable 28. Since the sleeves 36 and 38 are tapered internally and provided with slots 48 the turning of compression nuts 40 and 42 in the proper direction will compress and grip the cable 28. Thus, the cable 28 is directly connected to the leg 14. FIG. 9 illustrates another form of an end connection constituting a flat pad 50 at the extreme end of each of the flexible legs 14 instead of the end connecting element 16 shown in FIG. 1. The pad 50 is provided with holes 52 which are adapted to be aligned with holes 54 of the complementary flat pad 56 on the cable 28. Bolt means 58 may be used to secure the cable 28 to the flexible leg 14 by passing the same through aligned holes 52 and 54 of the pads 50 and 56 respectively.

It should be noted that the application of an insulating cover 24 to the multi-linked, flexible connector is accomplished either by dip-coating the insulation on the connector or by encapsulating or molding the same on the metal connector.

It should be further noted that the present multi-linked, flexible connector of heavy gauge material is provided with a multiplicity of connecting elements which are omni-directional. In addition, the connector 10 is completely insulated and, when installed, can be submersible. Accordingly, the present flexible connector can be located in confined or otherwise inaccessible locations by bending the flexible arms to convenient positions whereby a cable may be affixed thereto. The present device, therefore, achieves a complete independence of each lead of the flexible pre-insulated connector crab. In addition, a variety of relatively small cable sizes may be inserted in the passageways 18 of the connecting end elements 16 by means of selected soft aluminum inserts or shims which will compensate for the difference between the diameter of the cable and the diameter of the passageway 18. Thus, the same die can be used to crimp all ends of the connecting end elements 16 regardless of cable sizes utilized with the present connector.

What is claimed is:

1. A multi-linked connector of heavy gauge material for a wire comprising a plurality of elongated flexible legs, said legs being omni-directional, a tie bar interconnecting said flexible legs, an end connecting element at the end of each of said elongated flexible legs, and external insulating means covering at least substantially said tie bar, flexible legs and end connecting elements.

2. A multi-linked connector as claimed in claim 1 wherein said heavy gauge metal is aluminum.

3. A multi-linked connector as claimed in claim 1 wherein at least one of said connecting end elements is constituted of a ductile material suitable for accepting various types of crimps.

4. A multi-linked connector as claimed in claim 1 wherein each of said flexible legs is circular in cross-section.

5. A multi-linked connector as claimed in claim 1 wherein said end connecting element is provided with a pressure plate engaging an outer surface of said wire, a threaded stud on said pressure plate, and a threaded opening in said end connecting element through which said stud is screw-connected.

6. A multi-linked connector as claimed in claim 1 further comprising a collet-type connection on at least one of said flexible legs for releasably holding said wire therein, said collet having a pair of sleeves which are internally tapered and provided with slots and which engage both said flexible leg and said wire respectively, and a compression nut for each sleeve which when rotated in a selected direction will compress and grip said wire and said flexible leg together.

7. A multi-linked connector as claimed in claim 1 wherein said end connecting element is a flat pad having spaced holes therein, said wire being provided with a correspondingly-shaped end part provided with spaced holes therein that are adapted to be aligned with the holes in the flat pad of said connector, and securing means in said aligned holes for fastening said wire to said connector.

8. A multi-linked connector as claimed in claim 1 wherein said end connecting element is provided with an elongated passageway therein for accepting an end of said wire therein with a snug fit.

9. A multi-linked connector, as claimed in claim 1 wherein at least one of said end connecting elements is of a ductile crimpable type having an elongated passageway therein and provided with selected shims therein to enable the installation of a smaller size wire in said elongated passageway.

10. A multi-linked connector as claimed in claim 1 wherein said legs, tie bar and end connecting elements are integral.
